UNITED STATES PATENT OFFICE.

WILLIAM B. TUNSTALL, OF WORCESTER, MASSACHUSETTS.

PLAYER PIANO.

Application filed July 29, 1920, Serial No. 399,738. Renewed October 14, 1922. Serial No. 594,657.

To all whom it may concern:

Be it known that I, WILLIAM B. TUNSTALL, a citizen of the United States, residing at Worcester, in the county of Worcester and State of Massachusetts, have invented new and useful Improvements in Player Pianos, of which the following is a specification.

This invention is embodied in certain improvements hereinafter described and claimed, relating to the case and to the automatic playing mechanism of a player piano.

One object of the invention is to provide shiftable controlling means for the automatic playing mechanism, said controlling means being adapted to be stored in a retracted position when the piano is played manually, and so projected from the front of the case, when the piano is played automatically, that the operator may maintain a natural position of the hands and operate the controlling means without cramping and tiring the fingers.

Another object is to enable the movable panel which alternately covers and exposes the usual roll-carrying mechanism, to serve as a music rack when the piano is played manually.

Another object is to provide a housing for the pumping pedals, adapted to conceal said pedals when the piano is played manually, and to expose the pedals to permit automatic playing.

Another object is to enable the roll-carrying mechanism and the pumping pedals to be simultaneously covered and exposed, so that the piano may be adapted for either method of playing by a single operation.

Other objects of the invention will be apparent from the following description and the appended claims.

Of the accompanying drawings forming a part of this specification,—

Figure 1 is a perspective view of the case and keyboard of a player piano embodying the invention, the roll-carrying mechanism and pumping pedals being concealed.

Figure 2 is a vertical section on the plane indicated by line 2—2 of Figure 1.

Figure 3 is a view similar to Figure 1,

showing the roll-carrying mechanism and pumping pedals exposed.

Figure 4 is a section on the plane indicated by the line 4—4 of Figure 3.

Figure 5 is a section on line 5—5 of Figure 2.

Figure 6 is a section on line 6—6 of Figure 2.

Figure 7 is a perspective view of the panel which covers and exposes the pumping 60 pedals.

Figure 8 is an enlarged section on line 8—8 of Figure 4.

Figure 9 is an enlargement of a portion of Figure 4.

Figure 10 is a section on line 10—10 of Figure 9.

Figures 11 and 12 are fragmentary sectional views, showing certain connections hereinafter described.

The same reference characters indicate the same parts in all of the figures.

The case front of my improved piano includes substantially vertical portions 12, 12, above the keyboard 13, and a substantially vertical portion 14, below the keyboard, and preferably in the same plane with the portions 12.

Projecting forwardly from the vertical portions of the case front, above the keyboard, is an upper hood, indicated as a whole by the reference numeral 15. Projecting forwardly from the case front below the keyboard is a lower hood, indicated as a whole by the reference numeral 16.

The upper hood 15 has an inclined front wall, which preferably includes fixed upper and lower members 17 and 18, forming the upper and lower edges of an opening in the hood, and a movable panel 19 hinged at 19^a (Figure 4) to the lower member 18. The upper hood also includes fixed upright end members 20, on which the panel 19 rests when closed, as indicated by Figure 6.

The roll-carrying mechanism which includes the usual spools 21 and 22, is located within and adjacent to the inclined front of the hood 15. When the panel 19 is displaced, as shown by Figure 4, the roll-carrying mechanism is exposed, and when

the panel is closed, as shown by Figure 2, the roll-carrying mechanism is covered, the panel in the last-named position being inclined, and adapted to serve as a music rest.

5 Fixed to the inner side of the panel 19 are elements of mechanism for controlling the automatic playing mechanism, said mechanism including a casing 23, in which is pivoted a manually movable finger lever 10 24, forming an element of the tempo-controlling means, and a casing 25, having manually movable push buttons 26, forming elements of dynamic control.

The said controlling mechanism will be 15 more fully described in detail hereinafter, it being sufficient for the present to say that the casings 23 and 25 are adjacent to the swinging end of the panel 19, so that when the panel is displaced, as shown by Figures 20 3 and 4, said casings and the manually movable parts associated therewith, are projected forward, and are in such position that the operator, in moving said parts, can 25 maintain a natural position of the hand, and control the playing mechanism without cramping or tiring the fingers.

The lower hood 16 preferably includes a fixed bottom member 27, fixed end members 28, and a movable panel 29, adapted to slide 30 in guides 30, formed in and extending above the end members 28.

The usual pumping pedals 31 pertaining to the automatic playing mechanism are located within and adjacent to the panel 29, and are hinged at 32 to the fixed member 27, located immediately above the usual sound-controlling pedals 34.

The sliding panel 29 is adapted to gravitate to the closed position shown by Figures 40 1 and 2, and when in said position, covers and conceals the pumping pedals 31, without obstructing the sound-controlling pedals 34.

To enable the panels 19 and 29 to be 45 simultaneously operated, I provide connections between said panels, so organized that when the hinged panel 19 is displaced or swung forward, the sliding panel 29 is moved upward in its guides. Said connections are preferably embodied in lever arms 50 35, fixed to the panel 19 and projecting from the hinged end thereof, flexible cords or straps 36 attached at their upper ends to the arms 35, and at their lower ends to pulleys 55 37, journaled to rotate on horizontal axes below the key bed of the piano, said cords passing under loose guiding pulleys 38, larger pulleys 39 coaxial with and fixed to the pulleys 37, and cords or straps 40, fixed 60 to and partially wound upon the pulleys 39, and fixed at their lower ends to the sliding panels 29.

When the hinged panel 19 is moved from the position shown by Figure 2, to that

shown by Figure 4, the sliding panel 29 is 65 raised to expose the pumping pedals. When the hinged panel 19 is returned to the position shown by Figure 2, the sliding panel 29 is depressed by its own weight and covers the pumping pedals. 70

It will now be seen that the operator is enabled, by swinging the hinged panel 19 to simultaneously cover the roll-carrying mechanism and the pumping pedals, as indicated by Figure 1, and to expose said mechanism and pedals, as indicated by Figure 3. 75

A dynamic control means including the casing 25, is of the usual push-button type in common use, the usual push buttons 26 through which control is exercised, being 80 projected forward from the piano case when in position for use.

In tempo control means including the casing 23, the lever 24 is fulcrumed at 24^a, and the face 23^a of the casing 23 is so arranged 85 relative to the fulcrum 24^a, that when the fingers of the operator's right hand bear on said face, and the outer portion of the right hand thumb is engaged with the forked outer end 24^b of the said lever, the first joint 90 of the thumb is in such position that the thumb and the lever 24 may swing on substantially the same center, so that an easy lever-operating movement of the thumb is permitted, the casing 23 and lever 24 being 95 also projected forward from the piano case.

The other elements of the dynamic control and tempo control means embody nothing new with me.

I will, however, briefly describe the same 100 with reference to Figures 11 and 12.

The push buttons 26 of the dynamic control are adapted to open a valve 41^a (Figure 8), which, when opened, allows atmospheric pressure to pass through a tube 41 (Figures 3, 8 and 11), and force upward a diaphragm 42 (Figure 11). A double valve 43 is thus lifted from a seat 47, and closed on a seat 45, so that vacuum pressure is allowed to pass through the conduit 44 to the interior of a power pneumatic (not shown), the movable leaf of which is suitably connected with the hammer rail, or with the dampers of the piano action. When the operator releases the push buttons 26, atmospheric pressure is released from the diaphragm 42, and the valve 43 closes on its seat 47 and allows atmospheric pressure to enter through the seat 45, so that the leaf of the said power pneumatic returns to its 110 normal position. 115

When the lever 24 of the tempo control is operated, it acts through suitable connections, including a rod 48, on a pull wire 49 (Figure 12), which is movable in the casing 50 of a well known type of governor for the wind motor which operates the roll mechanism. The pull wire is connected with 120 125

a throttle valve 51, in the governor casing, and said valve regulates the speed of the wind motor as usual. The port through which air from the bellows enters the governor, is shown at 52. The orifice through which the pressure from the bellows passes is shown at 53. The spring valve adapted to be closed by a movement of the usual bellows leaf 55, is shown at 54. The spring on which 10 depends the amount of air pressure governed in this manner is shown at 56.

I claim:

1. A player piano comprising a case including a substantially vertical case front 15 above the keyboard, and a hood located between the ends and projecting forward from the central portion of said front, said hood having an inclined front wall which includes a hinged panel which is movable to 20 open and close the hood, roll-carrying mechanism extending forward from the case front into said hood, and rendered conveniently accessible by its forward extension when the hood is opened, said front 25 wall being inclined relatively to the case front and thereby adapted to serve as a music rest when the hood is closed, and manually operable means carried by said panel for controlling the operation of automatic 30 playing mechanism within the case, said controlling means being projected from the case front by the panel, and rendered conveniently accessible, when the hood is opened, and concealed by the panel when 35 the hood is closed.

2. A player piano substantially as specified by claim 1, the said panel being hinged at its lower edge, and caused to project forward from the case front when opened, and 40 said controlling means being located on the back side of the panel, and carried forward from the case front by the opening of the panel, means being provided for supporting the panel in a predetermined opened position, with the controlling means accessible 45 to the hands of the operator.

3. A player piano comprising a case including a substantially vertical case front below the keyboard, and a hood projecting forward from the central portion of said front, said hood having an inclined front wall which includes a hinged panel, which is movable to open and close the hood, and a fixed bottom member projecting forward 55 from the case front; pumping pedals connected with automatic playing mechanism within the case, and hinges fixed to the projecting portion of said bottom member and to said pedals, said hinges and the lower 60 portions of the pedals projecting from the case front, so that the pedals are conveniently accessible, the pedals being housed within the hood, concealed by the panel when the hood is closed, and covered by the 65 panel when the hood is opened.

4. A player piano comprising a case including a substantially vertical case front below the keyboard, and a hood projecting forward from the central portion of said front, said hood having an inclined front 70 wall which includes a hinged panel, which is movable to open and close the hood, and a fixed bottom member projecting forward from the case front; pumping pedals connected with automatic playing mechanism 75 within the case, hinges fixed to the projecting portion of said bottom member and to said pedals, said hinges and the lower portions of the pedals projecting from the case front, so that the pedals are conveniently 80 accessible, the pedals being housed within the hood, concealed by the panel when the hood is closed, and covered by the panel when the hood is opened; and sound-governing 85 pedals located below and projecting forward from the fixed bottom member of the hood, and operable when the hood is either closed or open.

5. A player piano comprising a case including a substantially vertical case front 90 below the keyboard, and a hood projecting forward from the central portion of said front, said hood having a front wall which includes a hinged panel which is movable to open and close the hood, and a fixed bottom 95 member projecting forward from the case front, the case being provided with inclined guides formed partly in the hood and partly within the case front above the hood, the panel being slidable in an inclined path in 100 said guides; pumping pedals hinged to the projecting portion of said bottom member, said pedals being connected with automatic playing mechanism within the case, and concealed by the panel when the hood is closed, 105 and covered by the panel when the hood is opened.

6. A player piano comprising a case including a forwardly projecting upper hood, located above the keyboard, and a forwardly projecting lower hood, located below the keyboard, roll-carrying mechanism within and adjacent to the front wall of the upper hood, pumping pedals within and adjacent to the front wall of the lower hood, and connected with automatic playing mechanism within said case, said front walls including 110 movable panels, one of which is hinged and the other slidable, and connections between said panels, adapted to convert a swinging movement of the hinged panel into a sliding movement of the sliding panel. 115

7. A player piano comprising a case, automatic playing mechanism therein, said case including a forwardly projecting upper hood, located above the keyboard, and a forwardly projecting lower hood, located below the keyboard, roll-carrying mechanism within and adjacent to the front wall of the upper hood, pumping pedals within 120 125

and adjacent to the front wall of the lower hood, said front walls including movable panels, one of which is hinged and the other slidible, and connections between said panels, 5 adapted to convert a downward swinging movement of the hinged panel into an upward sliding movement of the sliding panel, the latter being adapted to be moved downward by gravity when the swinging panel 10 is moved upward.

8. A player piano comprising a case, including a forwardly projecting upper hood, located above the keyboard, and a forwardly projecting lower hood, located below the 15 keyboard, roll-carrying mechanism within and adjacent to the front wall of the upper

hood, pumping pedals within and adjacent to the front wall of the lower hood, and connected with automatic playing mechanism within the case, the upper hood including a 20 panel hinged at its lower edge to swing outwardly, and the lower hood including fixed portions having guides and a panel slidible in said guides, and normally lowered and closed by its own weight, and connections 25 between said panels whereby, when the upper panel is swung downward, to expose the roll-carrying mechanism, the lower panel is raised to expose the pumping pedals.

In testimony whereof I have affixed my 30 signature.

WILLIAM B. TUNSTALL.
